UNITED STATES PATENT OFFICE.

SHERIDAN W. TROUT, OF JEANNETTE, PENNSYLVANIA.

TOY TARGET.

Application filed May 11, 1927. Serial No. 190,522.

This invention is for a mechanical toy, and more particularly a target for use in connection with shooting games.

The shooting games as ordinarily provided have targets which are usually of a stationary nature. According to the present invention there is provided a target which will be set in motion when the bull's eye is hit, so as to provide an added feature of action to the game. The extent of rotation of the target may also be used to indicate the number of points which each player wins and thereby combine with the shooting feature a game feature which will be both attractive and entertaining.

According to the present invention there is also provided a target which can be constructed cheaply and which will be simple to operate. The target is designed primarily for use with air guns which shoot corks as projectiles but, of course, is applicable for use with other shooting appliances.

The invention may be readily understood by reference to the accompanying drawing, in which

Figure 1 is a front elevation of the one form of toy embodying my invention.

Figure 2 is a side elevation of the construction shown in Figure 1.

The toy as illustrated comprises a supporting frame having a base 5 with an upright 6 at the back thereof. In the top of the upright is a pin 7 on which is carried a freely rotatable disk 8 forming the target. In the periphery of the disk are two or more notches 9. Mounted on the base 5 are upright ears 10 to which is pivoted a bell crank member by means of a pin 11. The bell crank member has a horizontal arm 12 with a terminal portion 13 adapted to be entered in one of the notches 9 in the periphery of the disk. The upright arm of the bell crank is designated 14 and has a bull's eye at its upper end, the bull's eye preferably being centrally located with respect to the disk 8. On the base 5 is an eye 16 to which is secured a rubber band or other resilient element, such as a spring 17.

The surface of the disk is preferably divided into segments by radially extending lines 18. Each segment may contain some indicia indicating a certain kind of game. Such indicia is indicated at 19. The indicia of the animal or game may consist merely of a printed word but preferably comprises the picture of the animal or other game. Each

segment may also contain a scoring numeral designated 19^a.

In operation, the terminal 13 of the horizontal arm of the bell crank is entered into one of the notches 9 in the disk. The rubber band or other spring element 17 is then stretched, and its free end entered into another one of the notches 9. The target is then set for operation. When the projectile hits the bull's eye 15, it rocks the arm 12, moving the terminal 13 down out of engagement with the notches 9 and the tensioned rubber band or other spring element then spins the disk. The band will, of course, become disengaged from the disk after it has imparted the spinning movement thereto, so that the disk can spin freely. When playing a game, the vertical arm 14 may serve as an indicator, but a pointer 12^a is preferably provided on the arm 12 close to the disk. The segment of the disk which stops under the pointer is the winning segment, and the player scores according to the marking 19^a in that segment.

The entire device can be cheaply constructed, and can be attractively colored or lithographed. Its construction and operation are extremely simple. One advantage of using a rubber band in place of any other spring for rotating the disk is the fact that it can be easily replaced when necessary.

While one form of the invention has been specifically illustrated and described in detail, it will be understood that various changes and modifications may be made in the construction and arrangement of the various parts within the contemplation of my invention and under the scope of the following claims.

I claim:

1. A toy target including a freely rotatable member, means for spinning the rotatable member, a detent cooperating with the rotatable member for normally holding the disk against rotation, and a movable target element operatively connected with the detent. 100

2. A toy target comprising a freely rotatable disk, means for spinning the disk, a movable detent element co-operating with the disk for normally holding it against rotation, and a target member carried by the detent. 105

3. A toy target comprising a freely rotatable disk, means for spinning the disk, 110

a pivotally supported detent member having a terminal co-operating with the disk for normally holding the disk against rotation, and an arm on the detent extending upwardly in front of the disk and having a target element thereon.

4. A toy target comprising a freely rotatable disk, means for spinning the disk, a pivotally supported detent member having a terminal co-operating with the disk for normally holding the disk against rotation, and an arm on the detent extending upwardly in front of the disk and having a bull's eye thereon centrally positioned with respect to the disk.

5. A toy target comprising a base, an upright on the base, a disk pivotally supported on the upright, a bell crank member pivotally supported on the base having a horizontal arm adapted to co-operate with the disk and having a vertical arm with a target element thereon, and resilient means secured to the base adapted to detachably engage the disk for spinning the same.

6. A toy target including a supporting frame with a base portion, a disk freely rotatable on the supporting frame and having a plurality of detent engaging elements about the periphery thereof, a bell crank member pivotally mounted on the base having a horizontal arm with a terminal adapted to co-operate with the detent engaging means on the disk, said bell crank having a vertical arm with a bull's eye thereon, and a resilient member secured to the frame having one end detachably engaging one of the detent engaging means of the disk.

7. A toy target comprising a supporting frame having a base, a disk freely rotatable

on the supporting frame, a resilient member secured to the supporting frame having one end thereof detachably engaging the disk for imparting a rotative movement to the disk when the same is released, a detent member on the base for normally holding the disk against rotation, and a target element connected with the detent.

8. A toy target comprising a supporting frame, a disk freely rotatable on the supporting frame, said disk having its surface divided into a plurality of sections, said disk having detent engaging means thereon, game indicia in at least some of the sections, a movable detent member adapted to cooperate with the detent engaging means of the disk for normally holding the disk against rotation, a target element carried by the detent member and resilient means for rotating the disk.

9. A toy target comprising a supporting frame having a base portion and an upright portion, a disk freely rotatable on the upright portion, said disk having notches in the periphery thereof, a lever pivotally mounted on the base portion having a terminal adapted to be entered in one of the notches in the disk, an upright arm on the lever member with a target surface thereon, a resilient member secured to the frame and having its free end entered into the other notch in the disk, said resilient member providing means for rotating the disk when the notch engaging lever is moved to released position by the impact of a projectile against the target.

In testimony whereof I have hereunto set my hand.

SHERIDAN W. TROUT.
